United States Patent

Des. 237,035
Patented Oct. 7, 1975

237,035

VACUUM CLEANER

Glenn E. Berendes, 142 W. Park, Butte, Mont. 59791,
and Robert D. Berendes, 30 Northern Pacific Ave.,
Belgrade, Mont. 59714

Filed Nov. 2, 1973, Ser. No. 412,445

Term of patent 14 years

Int. Cl. D7—05

U.S. Cl. D7—166

FIG. 1 is a perspective view showing the top and one side of vacuum cleaner; and

FIG. 2 is a perspective view of the vacuum cleaner showing the bottom and other side thereof.

The hose has been shown fragmentarily in FIGS. 1 and 2 for convenience of illustration.

We claim:

The ornamental design for a vacuum cleaner, as shown and described.
